UNITED STATES PATENT OFFICE.

EUGENE ADAMS, OF DUBUQUE, IOWA, ASSIGNOR TO THE ADAMS COMPANY, OF DUBUQUE, IOWA, A CORPORATION OF IOWA.

HINGE.

Application filed April 13, 1927. Serial No. 183,582.

This invention relates to new and useful improvements in hinges, and especially to hinges for utilization on foundry snap flasks, where rigid corners are essential. Obviously 5 however, its application is not limited to such structures.

The cope and drag of a molder's flask are usually of rectangular formation comprising a box-like structure adapted to enclose the 10 sand in which the impression is to be cast. The sides of the cope and drag are hingedly connected at the corners and are constantly being opened and closed during operation, thereby subjecting the hinged joints to wear. 15 It is essential that the rigid corners of the cope and drag be preserved, but, during the molding operations, sand is often inadvertently dropped upon the hinges, and the subsequent pivotal movements grinds the sand at 20 the pivot points of the hinge, causing a wear which ultimately destroys the rigid corner of the flask.

It is the primary object of the present invention to provide a hinge structure so 25 mounted as to permit easy adjustments to compensate for the wear to which the hinge is subjected, whereby the rigid corner may be substantially maintained.

Other objects of the invention will be made 30 apparent in the following specifications, when read in connection with the accompanying drawings forming a part thereof.

In said drawings:

Fig. 1 is a perspective view of one of the 35 corner hinges embodying my invention.

Fig. 2 is a top plan view of said hinge, partly in section.

Fig. 3 is a fragmentary detail, looking 40 downwardly upon the hinge joint, and,

Fig. 4 is a plan view of the hinge pintle, and associated washer and nut.

Now referring specifically to the drawings, in which like reference numerals indicate similar parts throughout the several views, 45 1 and 2 indicate adjoining walls of the cope or drag pivotally connected by a hinge 3. It is of course understood that one of the corners of the cope and of the drag is provided with suitable detachable fastening means, whereby to permit the swinging movements 50 of the walls 1 and 2 on the hinge 3.

The hinge 3 is formed of two leaves 4 and 5, each provided with apertures for the reception of screws or bolts 6, whereby to attach the leaf to the cope or drag wall. As

here shown the leaf 4 is provided with an apertured ear 7, projecting from and flush with the lower surface of the leaf 4, and with a similar ear 8 having its upper surface below the plane of the upper edge of said leaf. The leaf 5 is also provided with similarly formed ears 9 and 10, these structures being clearly illustrated in Figs. 1 and 2.

As shown most clearly in Fig. 2 the ears 7 and 9, and 8 and 10, are respectively connected by pintles or pins 11 and 12, terminating in a conically-formed screw head 13 and 14 respectively, seated in a properly shaped socket formed in the ears 10 and 7 respectively. In order to provide for adjustments to 70 compensate for wear caused naturally, and augmented by the sand being ground between the pintle heads 13 and 14 and the sockets in which they are seated, and between the contacting faces of the ears 7 and 9, and 8 and 10, 75 respectively, the walls forming the apertures in the ears 8 and 9 are internally screw-threaded, and the pintles 11 and 12 are each provided with a few threads engaging the threads in the ears 8 and 9. The apertures in the ears 7 and 10 are merely drilled, and the portions of the pintles 11 and 12 passing through such apertures, are free of screw threads. To lock the pintles 11 and 12 in set position, I utilize a washer 15 and a nut 80 16, mounted on the ends thereof.

With the instrumentalities positioned as above explained, and as illustrated in Figs. 1 and 2, it is clear that, when wear has taken place between the ears 7, 9 and 8 and 10 respectively, and between the head of the pintles 13 and 14 and their sockets, the rigidity of the corner of the cope or drag will be disrupted on account of looseness of the hinge 3 at the points referred to. To adjust the 90 pintles 11 and 12 to compensate for wear, the nuts 16 and washers 15 are backed off the ends of the pintles, and the heads 13 and 14 are each turned with a screw driver until the lower face of the head more or less lightly contacts the socket in which the head rests. It will be understood that, since each pintle is equipped with threads 17, which engages threads on the wall defining the apertures in the ears 8 and 9, rotation of the heads 13 or 14 will draw together the ears 7 and 9, and 8 and 10 respectively. When the necessary 95 adjustment is effected, the washer 15 and nut 16 are replaced.

In order to insure that the walls 1 and 2, 110

carried by the leaves 4 and 5, define an exact right angle, each of the leaves is provided with a flange 18 formed at an angle to the body portion, and forming a shoulder against 5 which is seated the edge of the wall 1 or 2. The vertical edges of the flanges 18, 18 are beveled at 19, as shown in Fig. 3, in order to insure a close fit at the corners of the walls 1 and 2.

- 10 In view of the foregoing it will be obvious that I have provided a structure which greatly facilitates adjustments to compensate for the wear which is incident to the continued use of hinges of this character.
- 15 Modifications of the structure herein disclosed may be suggested to those skilled in the art, but the invention covers all embodiments falling fairly within the scope of the appended claim.

- 20 I claim:
- A hinge for molders' flasks or the like com-

prising two leaf portions, each portion having ears extending therefrom in substantial contact with the ears on the other portion, an ear on one portion being provided with an internally screw threaded aperture and an ear on the other portion being provided with a smooth walled aperture having a centering enlargement, a pintle extending through the screw threaded aperture of one ear and the smooth walled aperture of the contiguous ear, and provided with threads adapted, under rotation of said pintle, to draw said contiguous ears together to compensate for wear, said pintle having surfaces contacting with said centering enlargement whereby to place said portions in proper alignment, and securing devices for rigidly holding said pintle in proper position.

In testimony whereof I affix my signature.

EUGENE ADAMS.
